UNITED STATES PATENT OFFICE

FRED ASHWORTH, OF WENHAM, MASSACHUSETTS, ASSIGNOR TO UNITED SHOE MACHINERY CORPORATION, OF PATERSON, NEW JERSEY, A CORPORATION OF NEW JERSEY

HEEL BREASTING MACHINE

Application filed November 6, 1930. Serial No. 493,859.

This invention relates to a machine for operating upon the heels of boots and shoes and particularly to mechanisms for trimming off the portion of the top-lift which projects beyond the breast of a Louis heel.

In the manufacture of women's shoes having Louis heels, the heel is frequently made of wood and covered, except as to the breast portion, with thin upper leather or other material of a color to correspond to the color of the upper. The breast portion of the heel is usually covered by a flap split from the grain face of the portion of the sole that extends from the heel seat. This flap is turned down and cemented to the breast face of the heel to cover the breast and also the edges of the material which is used to cover the remainder of the heel. A leather top-lift is attached to the tread face of the heel thus formed and the breast end of the top-lift is subsequently trimmed off flush with the leather covered breast face of the heel. The contour of the breast face of the heel varies with different sizes and styles of Louis heels which necessitates removing the cutting mechanism and replacing it with another whenever heels having different characteristics are to be breasted. The top-lift is trimmed flush with the heel breast and since there is a relative movement between the breasting knife and the heel breast, there is a possibility of damaging the heel breast covering.

An object of the present invention is to provide a readily detachable breasting unit for trimming off the projecting end of a top-lift flush with the heel breast in which a breasting knife and work support are arranged for relative movement.

A feature of the invention consists in the combination of a permanent frame, a permanent driving mechanism supported in the frame, and a detachable breasting unit comprising a relatively movable breasting knife and work support mounted upon the frame in co-operating relation to the driving mechanism. In the illustrated embodiment of the invention, the breasting unit is secured to a frame by means of a pair of bars having slots at their lower ends co-operating with a pair of members for rigidly and detachably

securing the breasting unit to the machine frame. The members co-operating with the locking means and the bars are so mounted that they may easily be unlocked to permit the ready removal of the breasting unit.

Another object of the invention is to provide an effective work gage and guard which will prevent marring of the heel breast covering.

Another feature of the invention, accordingly, resides in a heel breasting machine provided with a heel breasting knife and a combined work gage and guard movable with a heel and slideable upon a face of the knife transversely of its cutting edge.

In the drawings,

Fig. 1 is a perspective view of the machine;

Fig. 2 is a view, partly in section, of a side elevation of the machine;

Fig. 3 is a plan view of the gage and knife; and

Fig. 4 is an elevation, partly in section, of the knife and gage mounting.

In the illustrated embodiment of the invention, 6 represents the frame of the machine. The frame 6 is provided with bearings 8 and 10 in which a shaft 12 is journaled. The shaft 12 is rotated by a belt 14 and a pulley (not shown) and the stopping of the machine may be accomplished by shifting the belt to a loose pulley 16. An eccentric 18 is made fast to, or integral with, the other end of the shaft 12 for reciprocating the operating instrumentalities of the machine, as will herein-after be more fully described. The breasting unit 19, which includes a breasting knife 22 and a shear block or work support 20, is detachably secured to the frame 6 in such a manner that it may be readily removed from the frame when it is desired to substitute another operating head.

In the illustrated embodiment of the invention the shear block 20 is mounted for movement relatively to a breasting knife 22. The shear block 20, which acts also as a work support, is secured to a support 24 by means of cap screws 26. The support 24 which forms a part of the breasting unit 19, is adjustably attached to the detachable breasting unit 19 by means of a cap screw 30 which

passes through an elongated slot 32 in the support 24 to permit adjustment of the support relatively to the knife 22. The lower end of the support 24 is provided with a bolt 34 which has an enlarged end forming a bearing for a roller 36. The roller 36 engages the eccentric 18 which operates to impart a vertical reciprocating movement to the work support 20, thus causing relative movement between the work support or shear block 20 and the knife 22.

The upper surface of the shear block 20 which engages the tread surface of a top-lift 38 of a heel 40 is made at a pitch angle of approximately 4°. This angle may be varied depending upon the angle between the heel breast and the tread surface of the top-lift of the heel by substituting another shear block having a greater or smaller angle as desired. The shearing edge 42 of the shear block 20 is shaped to coincide with the shape of the co-operating breasting knife 22.

The knife 22 is rigidly and adjustably secured to the operating head of the machine by means of set screws 44 passing through slots 46 in bars 48. Supporting arms 50 of the breasting unit 19 slide on the knife-supporting bars 48. The knife is adjustably mounted so that it may be readjusted after it has become worn by grinding or for adjusting a fresh knife relatively to the shear block. The bars 48 extend down into bosses 52 formed in the frame 6 of the machine. Slots or grooves 54 are formed in each bar 48 and are engaged by pins 56 which are arranged to slide in horizontal bosses 58. The pins 56 hold the bars 48 in their proper position and the breasting unit 19 to the frame of the machine. A combined work guard and gage 60 made of relatively thin flexible metal and slidably mounted on the cutting face of the knife 22 transversely of its cutting edge is yieldably mounted on the bars 48 by sleeves 62 which slide on reduced end portions of the bars 48. The gage 60 engages a shoulder 61 on each of the sleeves 62 and, by means of springs 64 which are held under compression by pinned washers 66, is normally held in the position shown in Fig. 1 of the drawings.

In order that the breasting unit may be held in position and be removed or replaced readily the pins 56 are pivotally mounted at 68 to a lever 70 which is fulcrumed to the frame 6 by a pin 72. The upper end of the lever 70 is forked and journaled to provide bearings for a rod 74 which acts both as a pivot for a dog 76 and also as a handle for conveniently swinging the lever 70 about its axis to disengage the pins 56 from the slots 54. The dog 76 is held in the position shown in Fig. 2 by means of springs 78 which are secured at one end to the dog 76 and at the other end to the machine frame 6. The free end of the dog 76 engages a crossbar 80 which connects the lower ends of the supporting

arms 50. The free end of the dog 76 is spring-inclined so that it will not slip off of the bar 80. This construction causes the support to be returned to its original position after the support has been moved upwardly by the action of the eccentric 18 on the roller 36.

Although the parts of the machine have been described in detail, it may be well to summarize briefly the operation of the machine. A heel 40 is positioned on the shear block 20 with the breast face of the heel in contact with the gage 60, as shown in Fig. 2, while the shear block is in the position shown in Fig. 1. The eccentric 18 then engages the roller 36 thus raising the block and causing the knife 22 to shear off a projecting portion of the top-lift 38. At the same time the work gage 60 moves upwardly with the heel 40, thus preventing sliding contact between the heel breast and the knife of the machine. The work support 20 is then caused to return to its original position by the influence of the spring 78. If it becomes necessary for any reason to replace the breasting unit by another unit it is only necessary to rotate the lever 70 in a clockwise direction, as viewed in Figs. 1 and 2, which will cause the pins 56 to leave the slot 54 in the upright bars 48 and also cause the dog 76 to be swung away from the crossbar 80. The entire breasting unit may then be easily removed and another breasting unit substituted therefor.

Having thus described the invention, what I claim as new and desire to secure by Letters Patent of the United States is:

1. In a heel breasting machine, the combination of a permanent frame, permanent driving mechanism supported in the frame, and a detachable breasting unit mounted upon the frame in cooperative relation to the driving mechanism, said breasting unit comprising a relatively movable breasting knife and work support.

2. In a heel breasting machine, the combination of a permanent frame, permanent driving mechanism supported in the frame, and a detachable breasting unit mounted upon the frame, said breasting unit comprising a stationary breasting knife and a movable work support arranged in cooperative relation to said driving mechanism.

3. In a heel breasting machine, the combination of a permanent frame, permanent driving mechanism including an eccentric supported in the frame, a detachable breasting unit mounted on the frame, said breasting unit comprising a stationary breasting knife and a movable work support arranged in cooperative relation to said driving mechanism, and means mounted on the machine frame constructed and arranged to lock the breasting unit to the machine frame.

4. In a heel breasting machine, the combination of a permanent frame, permanent

driving mechanism including an eccentric supported in the frame, a detachable breast-
ing unit mounted on the frame, said breast-
ing unit comprising a stationary breast-
ing knife and a movable work support arranged
5 in cooperative relation to said driving mech-
anism, means constructed and arranged to
lock the breasting unit to the machine frame,
and means mounted on the locking means
10 normally tending to return the work support
to its work-receiving position.

5. In a heel breasting machine, the combi-
nation of a permanent frame, permanent
driving mechanism including an eccentric
15 supported in the frame, a detachable breast-
ing unit mounted on the frame, said breast-
ing unit comprising a stationary breast-
ing knife and a movable work support arranged
20 in cooperative relation to said driving mech-
anism, and a roller mounted on the movable
work support constructed and arranged to
cooperate with the eccentric to reciprocate
the work support.

6. In a heel breasting machine, the com-
25 bination of a permanent frame, permanent
driving mechanism including an eccentric
supported in the frame, a detachable breast-
ing unit mounted on the frame, said breast-
ing unit comprising a stationary breast-
30 ing knife and a movable work support arranged
in cooperative relation to the driving mech-
anism, and means constructed and arranged
to lock the breasting knife to the machine
frame.

35 7. In a heel breasting machine, a perma-
nent frame, means on the frame constructed
and arranged to receive a breasting unit, and
a detachable breasting unit mounted on the
frame, said breasting unit comprising a sta-
40 tionary breasting knife, means on the breast-
ing unit arranged to cooperate with the means
on the frame to detachably secure the breast-
ing unit to the machine frame, and a movable
work support arranged in cooperative rela-
45 tion to the driving mechanism.

8. In a heel breasting machine, the combi-
nation of a breasting knife and a combined
work gage and guard movable with a heel
and slidably upon a face of the knife trans-
50 versely of its cutting edge.

9. In a heel-breasting machine, the combi-
nation of a stationary breasting knife for
trimming off the projecting portion of a top-
lift of a heel, a movable heel support, and a
55 guard between the knife and the breast face
of a heel upon said support, said guard being
movable with the heel and arranged to pre-
vent contact of said breast face of the heel
with the knife.

60 10. In a heel breasting machine, the combi-
nation of a stationary breasting knife for
trimming off the projecting portion of a top-
lift attached to a heel, and a guard mounted
65 between the knife and the breast face of a
heel upon said support, said guard compris-

ing a thin flexible strip of spring-metal
mounted to move with the heel and tending
to return to its normal position, said guard
also being arranged to prevent contact of the
70 breast face of the heel with the knife.

11. In a heel breasting machine, a frame,
driving mechanism supported on the frame,
and a detachable breasting unit comprising a
breasting knife, a work support, and means
75 on the work support cooperating with the
driving mechanism for moving the work sup-
port relatively to the breasting knife.

12. In a heel breasting machine, a frame,
driving mechanism supported on the frame, a
breasting knife for trimming off the project-
80 ing portion of the top-lift of a heel, a mem-
ber constructed and arranged to engage the
breast face of the heel to prevent contact of
the knife with the heel breast, a work sup-
port arranged to cooperate with the breasting
85 knife to perform a trimming operation, and
means on the work support cooperating with
the driving mechanism to reciprocate the
work support relatively to the breasting
90 knife.

13. In a heel breasting machine, a frame, a
drive shaft mounted on the frame, an eccen-
tric on the drive shaft, and a detachable
breasting unit comprising a breasting knife,
95 a work support, and means mounted on the
work support cooperating with the eccentric
for relatively moving the work support and
breasting knife.

In testimony whereof I have signed my
name to this specification.

FRED ASHWORTH.
